Primary Examiner—Brian N. Vinson*Attorney, Agent, or Firm*—Franklin J. Cona[57] CLAIM

The ornamental design for a bathroom dental equipment support, as shown and described.

DESCRIPTION

FIG. 1 is top, front, and left side elevational view of a bathroom dental equipment support as embodied in a combination toothpaste dispenser and toothbrush holder showing my new design;

FIG. 2 is a top plan view thereof;

FIG. 3 is a bottom plan view thereof;

FIG. 4 is a rear elevational view thereof;

FIG. 5 is a left side elevational view thereof;

FIG. 6 is a right side elevational view thereof;

FIG. 7 is a front elevational view thereof;

FIG. 8 is a top plan view of the toothpaste tube tip and toothbrush holder portion, the remainder of the assembly being omitted for clarity of illustration;

FIG. 9 is a left side elevational view of the tube press portion, the remainder of the assembly being omitted for clarity of illustration;

FIG. 10 is a top, front, and left side elevational view of a bathroom dental equipment support as embodied in a toothpaste dispenser showing my new design, the only difference from the first embodiment residing in the configuration of the toothpaste tube tip portion; and,

FIG. 11 is an enlarged top, front, and left side perspective view of the embodiment of FIG. 1, the broken-line disclosure of a toothpaste tube and two toothbrushes being for illustrative purposes only and forming no part of the claimed design.
